UNITED STATES PATENT OFFICE

115,563

DESIGN FOR A SUPPORT FOR COAL AND WOOD RANGE OR THE LIKE

John R. Morgan, Oak Park, Ill., assignor to Sears, Roebuck and Co., Chicago, Ill., a corporation of
New York

Application October 8, 1938, Serial No. 80,326

Term of patent 7 years

To all whom it may concern:

Be it known that I, John R. Morgan, a citizen of the Republic of Guatemala, residing in Oak Park, in the county of Cook and State of Illinois, have invented a new, original, and ornamental Design for a Support for Coal and Wood Range or the like, of which the following is a specification, reference being had to the accompanying drawing, forming a part thereof.

The drawing is a perspective view of a support for coal and wood range or the like embodying my new design.

The side not shown is substantially similar to the side which is shown.

I claim:

The ornamental design for a support for coal and wood range or the like, as shown and described.

JOHN R. MORGAN.
